BABY FOOD WARMER

Elmer Michael O'Callaghan, Portland, Oreg.

Application July 6, 1948, Serial No. 147,392

Term of patent 14 years

(Cl. D44—1)

To all whom it may concern:

Be it known that I, Elmer Michael O'Callaghan, a citizen of the United States, residing at Portland, in the county of Multnomah and State of Oregon, have invented a new, original, and ornamental Design for Baby Food Warmer, of which the following is a specification, reference being had to the accompanying drawing, forming a part thereof.

In the accompanying drawing:

Fig. 1 is a top plan view of a baby food warmer showing my new design;

Fig. 2 is a bottom plan view; and

Fig. 3 is a side elevational view thereof.

I claim:

The ornamental design for baby food warmer, substantially as shown.

ELMER MICHAEL O'CALLAGHAN.
